UNITED STATES PATENT OFFICE.

MARTIN DE TAMBLE, OF INDIANAPOLIS, INDIANA, ASSIGNOR TO UNIVERSAL AUTOMATIC CARVING MACHINE CO., OF CHICAGO, ILLINOIS, A CORPORATION OF NEW JERSEY.

FEED MECHANISM FOR AUTOMATIC CARVING-MACHINES.

No. 921,091.

Specification of Letters Patent.

Patented May 11, 1909.

Application filed November 16, 1903. Serial No. 181,436.

To all whom it may concern:

Be it known that I, MARTIN DE TAMBLE, a citizen of the United States, residing at Indianapolis, in the county of Marion and 5 State of Indiana, have invented certain new and useful Improvements in Feed Mechanisms for Automatic Carving - Machines, of which the following is a specification.

My invention relates to automatic carving machines, and has special reference to improvements upon those machines wherein a transversely movable feed-table is employed on a longitudinally movable bed. In such machines, the bed with the table is regularly 10 reciprocated, and, as the bed approaches the end of its stroke in either direction, the table is fed slightly to one side, in order that the carving-tools may make fresh cuts during the return stroke of the bed. The devices heretofore employed for feeding the table in this manner have been of such construction and arrangement as to require considerable time for their operation, with the result that the table has not been set over simultaneously 15 with the termination of the longitudinal stroke of the bed and table, nor approximately so. This has occasioned the irregular action of the cutters. Furthermore, the present feeding-mechanisms are incapable of 20 either fine adjustment or great range of adjustment; yet both these qualities or abilities are essential to the fine performance of a variety of work. The automatic carving machine which I believe to be, of all, the most 25 satisfactory and practical is that which is made in substantial accordance with Letters Patent No. 696,382, granted to Streich and Ruehs, March 25th, 1902. This machine, however, is subject to the foregoing criticism, 30 for it has a feed-mechanism that is actuated by the last part of the stroke of the bed, and the action of which is rendered still more uncertain by the presence of springs or cushions between the bed and its driving-mechanism. These springs or cushions are 35 compressed by the movement of the table against the resistance of the tracer and the tools, and as a result, when the driver is reversed, the table has a short, independent forward 40 movement, followed by a period of delay, before it is picked up by the reversely operated driver. This feature of the machine is objectionable, so far as the feed-mechanism is concerned; but the intermittency and yet 45 continuousness of the action obtained in the

table through the employment of the yielding connections is of the greatest advantage in reproducing high - relief carvings, and should be retained.

My conception is that the transverse feed- 60 movements of the work-table, instead of preceding the moment of table-delay, should take place during such period and just precede the beginning of each stroke of the table and bed; and the object of this invention is to 65 provide an improved table-feeding mechanism, whereby the table shall be fed simultaneously with or just preceding the beginning of each stroke.

Another object of my invention is to pro- 70 vide a table-feeding mechanism that shall be readily adjustable to vary the feed of the table; and which, furthermore, may be regulated or adjusted during the operation of 75 the machine.

Still another object of my invention is to improve the means or mechanism that is employed for reversing the direction of the transverse movement or feed of the table; and still another object of my invention is to 80 provide a table-feeding mechanism that shall constitute an unbroken connection between the bed-driving mechanism and the table; throughout which, the parts shall be in positive engagement at all times.

With these objects in view, my invention consists in the improvements in feed mechanism for automatic carving machines as hereinafter described and particularly pointed out in the claims.

The invention will be more readily understood by reference to the accompanying drawings, forming a part of this specification, and in which:—

Figure 1, is an elevation of the front end of 95 an automatic carving machine equipped with a feed mechanism embodying my invention, the upper portion of the machine being broken away; Fig. 2, is an end view of the parts shown in Fig. 1; Fig. 3, is a plan view 100 of the machine, the feed table being removed, to disclose the underlying parts; Fig. 4, is an end view of the oscillatory feed-clutch; Fig. 5, is a sectional view thereof, substantially on the line $x-x$ of Fig. 4; Fig. 6, is an end view 105 of the variable stroke feed-pawl; Fig. 7, is a side view thereof; and Fig. 8, is a sectional view of the hand feed-control.

As shown in the drawings, 2 represents the frame of an automatic carving machine. 3

is the longitudinally movable bed, and 4 the transversely movable feed-table that rests upon the bed. 5 represents the bed-driving mechanism, which, with the shifter, 6, operates to reciprocate the bed, 3, upon the frame, the same being automatically reversible. The construction of these parts of a carving machine is too well understood to require detailed explanation herein.

- 10 A worm, 7, is usually employed in connection with the driving device, and this coöperates with a rack, 8, that is yieldingly connected to the bed by springs or cushions, 9, above referred to. In place of the worm, 7, a screw 15 may be used with a nut in the center of the table, having springs on either side thereof. In such case this nut will take the place of and operate as the rack, 8. These cushions, 9, and their functions are fully described in 20 No. 757,243; and the purpose thereof is to permit the bed and feed-table to lag with respect to the movement of the driving-mechanism, whenever the table encounters special or abnormal resistance from the tracer and 25 the cutters which operate upon the pattern and work that are upon the table. It is obvious that there is a moment of complete stoppage or delay at the end of each stroke of the bed, preceding the actual reversal of the 30 driving-worm, 7. This period of delay is prolonged by the time required for the recovery of the cushions, following the stoppage of the worm, 7, and by the time required for the picking up or starting of the bed by 35 the driving-worm, through the medium of said cushions. It is during these periods of delay that I desire to feed the table upon or across the bed, although, as it will be evident hereinafter, the feed movement may, and 40 would, in the absence of the cushions, with good results, take place simultaneously with the actual reversal of the bed.

My feed mechanism comprises five principal elements or mechanisms, that, together, 45 extend between and positively connect the bed-driving mechanism and the feed-table. These parts are: The clutch, A; the feed-regulator, B; the pawl-throwing disk, C; the ratchet mechanism, D; and the sliding-connection, E, between the ratchet mechanism and the feed-shaft or spindle, 10, wherefrom the actual transverse movement is communicated to the table. A, the first of the mechanisms, comprises two friction-disks, 11 and 50 12. The part, 11, is arranged on a shaft, 13, having bearings, 14 and 15, in the machine frame and carrying a large beveled gear, 16. The shaft, 13, and the clutch-part, 11, are driven by the pinion, 17, this pinion being 55 on the worm shaft or on a shaft just below that carrying the worm or bed-driver, 7, and rotated in time therewith by any suitable means, such as suitable gearing 7'. Said shaft, 13, is therefore first driven in one direction and then in the other, according to the

reversals of the driver by the mechanism, 5. In Fig. 1 the relation of the shaft carrying the worm, 7, to the shaft beneath, which latter carries the gear, 5, is clearly shown by dotted lines. In Fig. 3 the lower shaft is covered 70 and concealed by the worm shaft and its bearings. The gears 5 and 17 are both on the lower shaft. The second part, 12, is secured to the oscillating or rocking shaft, 18. On one end of this shaft is the bearing, 19, in the 75 end of the disk, 11; the two shafts, 13 and 18, abutting therein. The opposite end of the shaft 18, has a bearing 20, in the side frame of the machine, and on its outer end carries the pawl-throwing disk, C. The part 12, as 80 shown in Fig. 5, is cup-shaped, to receive the disk, 11, and said part 12 is supplemented by a spring-pressure ring or disk, 21, arranged on the opposite side of the disk, 11, and held against the same by springs, 22, provided on 85 studs, 23, that are placed around the part 12. The pressure of the outer disks, 12 and 21, upon the disk, 11, may be varied by means of the follower-nuts, 24, on the studs, 23. Leather washers, 25, are preferably arranged 90 between the disks, to increase their frictional engagement.

The second mechanism, B, is the feed-regulator, and comprises a device for limiting and adjusting the throw or oscillation of the 95 part, 12, and the shaft, 18. This regulator comprises the pins, 26, provided on the face of the disk, 12, and the sliding yoke, 27, with its operating rod, 28. The yoke, as shown in Fig. 4, embraces the hub, 12', of the disk, 12, 100 and is provided with oppositely-extending stop-lugs, 29, 29, that have curved stop-surfaces, 29'. Any suitable means may be arranged for moving the rod, 28, and the yoke; such, for example, as the hand-wheel, 30, 105 having an internally-threaded sleeve or hub, 31, held in a bearing, 32, of the frame and engaging the threaded end, 28', of the regulating-rod, 28. By these devices, the yoke may be so adjusted that its lugs will engage 110 both pins upon the disk, 12, or it may be retarded, to free said pins and the disk, 12, for partial rotation or oscillation by the friction-disk, 11.

The third element of the feed-mechanism 115 is the simple disk or cross-arm, C, on the end of the shaft, 18, and to which the lower ends of the pawl-bearing links, 33, 34, are pivoted.

The fourth element is of a somewhat more complicated nature, and is composed of the 120 ratchet-wheel, 35, arranged on a short shaft, 36, together with the operating dogs, 39, 40, that are pivoted on the oscillating levers, 37, 38. The links, 33, 34, have their upper ends pivoted to the lower ends of the levers, 37, 125 38, and said levers are journaled on the shaft, 36. Said shaft, 36, is rotatable in the small bearing, 41, arranged in the machine-frame, 2. The ratchet-wheel, 35, has a great number of notches, 35', for engagement with the 130

oscillating pawls or dogs, 39, 40, as shown in Figs. 2 and 6. The parts 39 and 40 may be defined as double-ended pawls, and are journaled on the horizontal studs, 43 and 44, upon the upper ends of the throw levers, 37 and 38. For holding the pawls in engagement with the ratchet-wheel, 35, I provide each with a small, weighted lever, 45. These levers are journaled on respective studs or pins 43—44, and each is provided with a stop-lug, 46, to engage either one of the shoulders, 39', 39"—40', 40", of the pawl to which it belongs. When thrown to one side, these weighted levers hold the corresponding ends of the pawls upon the ratchet-wheel, and when thrown to opposite positions they operate to engage the other ends of the pawls with said wheel, 35, whereupon the rotation of the latter will be reversed. Though rotatively intermittent, the ratchet-wheel's direction of rotation remains the same, so long as the weights, 45, of the pawls remain unchanged, and the same may therefore be employed for continuously driving or feeding the table across the bed.

The shaft, 36, of the ratchet, carries the bevel pinion, 42, arranged on the inner end of the stationary bearing, 41. This pinion, with the parts associated with it upon the reciprocating bed of the machine, constitutes the fifth element or mechanism, E, of my machine, the purpose thereof being to maintain a constant connection between the feeding-mechanism or ratchet-device and the feed-table gearing, and to communicate the intermittent and variable movement of the ratchet-mechanism to the feed-table, or, in place thereof, to the chucks, on the table, by either of which motions the work may be fed transversely to the carving-tools.

With the exception of the motion-communicating shaft, 53, that is arranged on the bed of the machine, this invention is not concerned with the detailed construction and arrangement of the parts that directly communicate the feed motion to the table, and my invention admits of the employment of any style, type or kind of mechanism that may be actuated from the ratchet-wheel or its shaft. The drawings hereof therefore illustrate only one of the systems of spindles and gears that I may employ on the feed-table. Referring again thereto, it will be seen that the shaft, 53, is held in bearings, 54, at the ends of the bed, 3, and that the gear, 42, is connected therewith by means of a beveled pinion, 51, that is held in a bracket, 52, on the bearing, 41. A feather-and-slot connection is used between the pinion, 51, and shaft, 53, and said shaft is therefore permitted to reciprocate through the pinion, 51, while said pinion is at all times engaged with the shaft to partially rotate it when motion is imparted to the ratchet-mechanism, D.

10, represents the main driving-shaft of

the table gearing. At its outer end this is held in a bearing, 48, and the shafts, 53 and 10, are connected by the beveled gears, 55 and 57. The inner end of the shaft, 10, is held in the sliding bearings, 4', that hang 70 from the table, 4, and gears, 59, are used for connecting the shaft, 10, with the worm-shaft, 50, for operating the chucks on the table, 4. The gears, 59, may be placed in mesh or disengaged at the will of the operator. 75

47, 47 represent the table-driving spindles that are arranged in bearings, 48—48 on the bed, 3, and which are connected to the table, 4, by the depending threaded sleeves, 49. Gears, 58, are used for connecting the shaft, 80 10, to one of the spindles, 47. This connection may be made at the same time with the connection to the worm-shaft, 50, but ordinarily the worm-shaft, 50, is not driven during the transverse movement of the table, by 85 the screw-spindles, 47. As shown in Fig. 3, the spindles, 47, on the front and back of the bed, are connected by a longitudinal shaft 47'.

It will be observed from the foregoing that pieces of work and the pattern that are held 90 in the chucks on the table may be either rotated or moved transversely across the bed, 3, or, if desired, both feeding movements may be used, all from the intermittent motion of the shaft, 53. The degree of movement imparted to the table by each stroke of the oscillating pawls of mechanism D, may be altered or regulated at any time by the manipulation of the stop-yoke or regulator, B, which alone controls the length of stroke 100 that will be imparted to the ratchet-pawls by the oscillator, C. Furthermore, as the ratchet-mechanism, D, is at all times positively engaged and connected with the table-gearing, through the medium of pinions, 42 105 and 51, such regulation of the ratchet-mechanism may be accomplished without interrupting or stopping the movement of the bed and the table thereon.

The uses, functions and advantages of my 110 invention may be summarized as follows:

When the reversing mechanism, 5, is started, the immediate result is the regular reciprocation of the bed which carries the feed-table. This reciprocation is brought 115 about by the periodical reversal of the driver, 7, due to the operation of the shifter by the bed itself. Because of its connection with the driver, 7, through the gears, 16 and 17, the shaft, 13, with the disk 11 thereon, will 120 be driven continuously in one direction throughout each operation of the driver, 7, and until said driver is reversed, whereupon the direction of rotation of the friction-disk, 11, will also be reversed. The use of the 125 small pinion, 17, on the driver-shaft, and the large gear, 16, on the shaft 13, considerably reduces the relative number of revolutions made by the shaft, 13; nevertheless, said shaft is preferably arranged to make several 130

revolutions during the operation of the driver. It is obvious, therefore, that except for the presence of the regulator, B, the shaft 18 would be constantly rotated, and that the presence thereof prevents complete revolutions of said shaft and confines its motions to oscillations that are exactly timed with the reversals of the bed-driver. The operation of the bed by the worm or driver, 7, is much more deliberate than the movement of the oscillating part thereby, and it follows that the feed-mechanism completes its operation before the movement of the table is perceptible.

15 The frictional engagement between the disks making up the friction-clutch is sufficient to cause the part, 12, to turn with the disk, 11, until one of the pins on the part, 12, engages with one of the lugs, 29, of the regulating-yoke, after which the disk, 11, rotates without affecting the disk, 12. When the disk, 11, is reversed, the disk 12 turns back therewith until the opposite pin, 26, engages with the opposite part of the yoke, 29. Said 20 yoke, as explained, is adjustable by means of the hand-wheel, 30, on the front of the machine, and when the same is moved it operates to further limit or increase the stroke or oscillation of the disk, 12, and shaft, 18, and consequently of the part C. In this 25 manner I make it possible to actually stop the oscillation of the ratchet-pawl or cause the same to take the maximum stroke of the part, C, imparted thereto through the medium of the constantly-driven disk, 11. The 30 two pawls of the ratchet-mechanism work oppositely; that is, one operates to positively move the ratchet, while the other is moving through its return stroke, and it is obvious 35 that as long as corresponding ends of the double pawls remain in engagement with the ratchet-wheel, said wheel will be intermittently rotated in a single direction. Said rotation of the ratchet-wheel is continued until 40 the feed-table of the carving machine has accomplished the needful transverse movement upon the bed, whereupon it is stopped to receive new pieces of work. After the new work has been placed upon the machine, the table need not be manually returned to its original position, but may be caused to feed back slowly, by the mere throwing or reversal of the weights, 45, belonging to the double pawls, such change of 45 position operating to engage the opposite ends of the pawls with the ratchet-wheel and cause it to rotate in the other direction. The motion of the ratchet-wheel by either of the pawls does not take place until the 50 driver is actually reversed. In addition to the foregoing, it should be understood that the table does not immediately take on the motion of the driver, because of the cushion-springs that are interposed between the rack, 55 8, and the bed, and that for this reason the 60 65

feed-mechanism actually accomplishes its full function of transversely feeding the table or the chucks thereon, prior to the beginning of the movement of the bed and table, in either direction.

70 The term "longitudinal motion or reciprocation" as applied to the operation of the machine, is intended to mean or designate the normal or constant action of the table; and the terms "transverse feed of the table," 75 "transversely feeding the table" and the like, are intended to mean or designate the transverse or lateral motion that is imparted either by the table itself or to any part by which the feeding of the work in a horizontal 80 plane or by rotation, is accomplished.

The shafts, 10, 47 and 50 are all connected at the same time, so that the work can be turned at will. For instance: If an oval piece of work were put on the centers and this piece of work exceeded in depth the lift of the tracer-bar, it would not swing under the tracer-point if the tracer-point were placed at the center of the pattern with the work running directly on the center. However, if the tracer-point is put on the center of the pattern and both feeds are thrown in, the pattern revolves on the centers and also moves laterally, thus enabling the tracer to reach every part of the pattern and still be 90 within the lifting range of the retracting mechanism; and when one side of the oval is finished thereby, the pattern may be turned over and the other side finished.

95 It is obvious that numerous modifications 100 of my invention will readily suggest themselves to one skilled in the art, and my invention is not confined to the specific constructions herein shown and described.

Having thus described my invention, I 105 claim as new and desire to secure by Letters Patent:—

1. In an automatic carving machine, a reciprocating bed and a feed-table, in combination with a suitably driven bed-driver, a cushioned connection between said bed and driver and a table-feeding mechanism actuated by said driver during the recovery of said cushioned connection following the longitudinal stroke of said bed and feed table in 115 each direction, substantially as described.

2. In an automatic carving machine, a reciprocating feed-table, in combination with a driving and reversing mechanism therefor, a table feeding mechanism including a partially revoluble friction-member and a rotative friction-member interposed between the table and the driving mechanism and connected to both, substantially as described.

3. In an automatic carving machine, a reciprocating feed table, in combination with a driving and reversing mechanism therefor, a step by step mechanism coupled to said table and operable to feed the table transversely, a friction mechanism whereby said 125 130

step by step mechanism is connected to and driven by said driving mechanism, one element of said frictional mechanism being alternately rotated in opposite directions, and the other element being provided with bosses or lugs, and an adjustable device provided with stop lugs for engagement with said lugs or bosses to limit the oscillatory movement of said second frictional member, substantially as described.

4. In an automatic carving machine, a longitudinally movable bed and a transversely movable table, in combination with bed-driving means yieldingly connected to said bed and a feed-mechanism for moving said table upon the bed after said bed has reached the end of its stroke, substantially as described.

5. In an automatic carving machine, a reciprocating feed-table, capable of transverse motion, in combination with a rotary driver therefor, and a table-feeding mechanism that includes a friction-clutch, one member of which derives oscillatory motion from successive reversals of said driver, substantially as described.

6. In a carving machine, the table to be operated, in combination with two frictionally-engaged rotary members, with means for rotating one of said members in first one direction, then the other, means for limiting the rotation of the other, and table-actuating means interposed between the latter member and the table, substantially as described.

35 7. In an automatic carving machine, the frictionally-engaged members, in combination with means for continuously actuating and periodically reversing one thereof, stops upon the other member, an adjustable device for limiting the movement of said stops, a feed table or workholder, and operating means interposed between said other member and said holder substantially as described.

45 8. In an automatic carving machine, the frictionally engaged members, in combination with means for rotating and periodically reversing one of said means, adjustable means preventing the complete revolution of the other member and determining the oscillatory movements thereof, a feed table or workholder and operating means interposed between said other member and said holder substantially as described.

55 9. In an automatic carving machine, a frame and a bed, in combination with the feed-table movable thereon, means for reciprocating said bed, a feed-mechanism on said frame, a yielding connection between said mechanism and said table and an operating connection between said mechanism and the bed-reciprocating means, substantially as described.

10. A carving machine table or work

holder, in combination with a feed-mechanism including a friction device comprising two members, one of which derives oscillatory motion in partial revolutions from successive reversals of rotation of the other, and means for communicating the movement of the oscillatory member to the work holder, substantially as described.

11. A carving-machine table or work holder, in combination with a feed mechanism, including a friction device, one member of which is rotated and periodically reversed and the other member of which is partially revolvable with the first member, and adjustable means for varying the limits of movement of said other member, to vary the feed of said holder, substantially as and for the purpose specified.

12. In an automatic carving machine, the reciprocating bed, in combination with work-carriers thereon, a driver for reciprocating said bed, a friction-member revolvable with and by said driver, a second friction-member engaging the first member and driven thereby, adjustable stops limiting the movement of the second friction-member by the first and work-moving mechanism actuated by said second member, substantially as described.

13. In an automatic carving machine, the frame, in combination with the bed, the table transversely movable on said bed, and adapted for longitudinal movement therewith, a bed-driver provided in said frame for reciprocating said bed, a table-feeding mechanism arranged on said frame and bed, a rotary connection between said driver and mechanism, and a regulator upon the front of the frame whereby the attendant may regulate the operation of said table-feeding mechanism at will, substantially as described.

14. A carving machine work table, in combination with a device for moving said table and actuating mechanism for said device comprising a friction disk, a second friction disk opposed to the first and connected with said device, means for rotating and periodically reversing the first friction disk, stops upon the second friction disk and other stops for engagement therewith, the latter stops being adjustable in proximity to said second disk, for regulating the movement of said second disk and the said device, substantially as described.

15. A carving table, and a device for moving the same, in combination with a table feed device, actuating mechanism comprising a rotated and periodically reversed friction member, a second friction member, opposed to the first and connected with said device, the shafts of said members, a yoke perpendicularly movable with relation to said shafts, manual means for moving said

yoke, and stops upon the second friction-member for engagement with said yoke, substantially as described.

16. In an automatic carving machine, a bed, in combination with work-carriers thereon, a driver for reciprocating said bed, a feed-mechanism for moving said work-carriers, means whereby said mechanism is actuated by said driver and means for regulating the 10 operation of said mechanism during the operation of said driver, substantially as described.

17. In an automatic carving machine, a feed table, in combination with a table-moving device, a ratchet-wheel connected with said device, pawl-levers, double pawls thereon, variable stroke means for moving said levers and hence said pawls and reversing means governing said pawls, substantially as 20 described.

18. In an automatic carving machine, a frame, in combination with the bed for reciprocation thereon, a driver for reciprocating said bed, a shaft held in bearings on the 25 end of said bed, a table transversely movable on said bed, table feeding means connecting said shaft and said table and a rotary part, E, for rotating said shaft, a bearing on said frame wherein said part E is held, said shaft 30 being slidably connected to said part E, and an operating connection between said driver and said part E, substantially as described.

19. In an automatic carving machine, the frame, in combination with the reciprocating bed thereon, transversely movable work-holders on said bed, a longitudinal shaft in 35 said frame, a bed-driver thereon, means for reversing the rotation of said shaft and driver, a transverse shaft geared to the

driver-shaft, a friction-disk thereon, an opposed friction-disk, a shaft connected with the latter, a work-feeding device actuated thereby and connected with said work-holders for moving them, and means for regulating the rotary movements of said opposed 45 friction-member, substantially as described.

20. In an automatic carving machine, the frame, the bed and the table equipped with work holders, in combination with a bed-driver, means for rotating and reversing 50 said driver, a shaft deriving alternative partial rotary motion only from said driver, a cross-arm thereon, a ratchet-wheel operatively connected with said table, pawl-levers having pawls for engagement with said 55 ratchet-wheel and links connecting said levers and cross-arm for moving the work holder, substantially as and for the purpose specified.

21. In an automatic carving machine, the frame, the reciprocating-bed and the feed-table, in combination with a driver, means for rotating and periodically reversing said driver, a rack engaged with said driver and having cushioned connections with said bed, 60 a friction-disk, suitable means connecting said disk and driver, an opposed friction-disk, means preventing complete revolutions of the latter and a table-feeding mechanism actuated by said opposed friction-disk, substantially as described.

In testimony whereof, I have hereunto set my hand, this 30th day of October, A. D. 1903, in the presence of two witnesses.

MARTIN DE TAMBLE.
